Application April 1, 1948, Serial No. 145,474

Term of patent 3½ years

(Cl. D34—15)

To all whom it may concern:

Be it known that we, Guy McCandless and Oliver W. Dunbar, citizens of the United States, and residents of the city of St. Louis, State of Missouri, have jointly invented a new, original, and ornamental Design for a Child's Amusement Device, of which the following is a specification, reference being made to the accompanying drawing, forming a part thereof, in which Figure 1 is a perspective view of a child's amusement device embodying our new design; Figure 2 is a top plan view thereof; Figure 3 is a front elevational view thereof; and Figure 4 is an end view thereof.

We claim:

The ornamental design for a child's amusement device, substantially as shown.

GUY McCANDLESS.
OLIVER W. DUNBAR.
